[57] ABSTRACT

A flyback EHT and sawtooth current generator for television display apparatus including a transformer and switching means connected thereto which are conducting during a scan period and are non-conducting during a flyback period, and reactances whether parasitic or not connected to the transformer which together with the transformer constitute a network having a minimum of three prescribed resonant frequencies during the flyback so that a scan which is substantially without any oscillations and a flyback EHT pulse having a wide and flat peak is produced.

FLYBACK EHT AND SAWTOOTH CURRENT GENERATOR HAVING A FLYBACK PERIOD OF AT LEAST SIXTH ORDER

The invention relates to a flyback EHT and sawtooth current generator particularly for television display apparatus, including switching means which are periodically non-conducting during a flyback period τ and are conducting during a scan period $T - \tau$ and a network having input terminals connected to the switching means, said network comprising a transformer having at least one primary winding and possibly one or more coils connected thereto, through which said sawtooth current flows during the scan period, and a secondary winding to which a rectifier circuit is connected for generating said EHT from the voltage pulses occurring during the flyback period at the secondary winding, said network having during the flyback period a first resonant frequency f_α which is at least substantially equal to the expression

$$(K/2 \tau) [1 + (4/\pi^2 K^2) (\tau/T - \tau) (1 - \frac{1}{2}S)]$$

in which $K = 1$ and S is a correction factor which is equal to the relative reduction of the slope of the sawtooth current at the end of the scan period relative to this slope at the centre of the scan period, and a second resonant frequency f_ϵ which is at least substantially equal to the said expression for $K = 5$.

It is known from the Netherlands Patent Specification 88020 and from the book "Televisie" by F. Kerkhof and W. Werner, third edition, chapter XIII to use a transformer having one or more primary windings and a secondary winding in flyback EHT and sawtooth current generators for television display apparatus and to proportion the impedances of the circuit elements present such as the transformer windings, the leakage inductance between the primary windings and the secondary winding, the inductances of the coils which are generally connected to a primary winding as well as the parasitic and non-parasitic capacitances in such a manner that hardly any or no free oscillations occur in the secondary voltage during the scan period. Such free oscillations have the drawbacks that useful energy is lost, that this useless energy is mainly dissipated in the transformer so that overheating of the transformer may occur and that the switching means conducting during the scan period may become prematurely non-conducting in case of large free oscillations.

The above-mentioned literature shows that said circuit constitutes a 4th-order network during the flyback period with two resonant frequencies and that the said free oscillations may be maintained low by proportioning the circuit elements in such a manner that these two resonant frequencies f_α and f_ϵ have very defined values which are dependent on the duration of the flyback period τ and the duration of the scan period $T - \tau$. As is apparent from the expression given in the preamble, the optimum value of f_α and f_ϵ is also slightly dependent on the extent to which the slope of the sawtooth current flowing through the deflection coils varies when the so-called S-correction of this current is used.

In addition to the requirement that the scan period must be without free oscillations a quite different requirement imposed for EHT and sawtooth current generators is that the EHT generated varies as little as possible when the EHT load varies. The generated EHT is

generally used in television display apparatus as an acceleration voltage for the beam current in the display tube in which the average magnitude of the beam current, which is dependent on the average luminance of the scene displayed, constitutes the EHT load. The extent to which the generated EHT is dependent on its load is expressed by the so-called EHT R_i which is the quotient between an EHT variation and the beam current variation causing this EHT variation. As the EHT R_i of a flyback EHT and sawtooth current generator is lower, the EHT is less dependent on its load. This is of great importance because a high EHT R_i (internal resistance) causes great power losses in the generator while a constant EHT furthermore benefits the optimum adjustment of other magnitudes dependent on this EHT such as, for example, deflection and convergence in colour television display apparatus.

With the object of reducing the EHT R_i of a flyback EHT and a sawtooth current generator while maintaining substantially no free oscillations during the scan period, the Applicant's Netherlands Patent application 6714750 proposes to proportion the network in such a manner that the second frequency of the said resonant frequencies is at least substantially equal to the expression mentioned in the preamble for $K = 5$ (fifth harmonic tuning) while in addition the inductance (partly leakage inductance) and the capacitance (partly parasitic capacitance) present between the primary windings and the secondary winding are chosen to be such that the flyback pulse applied to the EHT rectifier has a peak which is as wide and as flat as possible. In fact, a wide and flat peak of this pulse means that the EHT rectifier conducts during a large part of the flyback period and as a result a reduction of the EHT R_i of the circuit arrangement to approximately $1 \text{ M}\Omega$ is obtained.

An object of the invention is to provide a flyback EHT and sawtooth current generator in which a considerable further reduction of the EHT R_i (to approximately $200 \text{ K}\Omega$) is possible while maintaining substantially no free oscillations and to this end the flyback EHT and sawtooth current generator according to the invention is characterized in that said network includes further reactances increasing the order of the network during the flyback period to a minimum of 6 to such an extent that the network has a third resonant frequency f_u while is at least substantially equal to the above-mentioned expression for $K = 7$.

It is essential for the invention that by a suitable addition of reactances and/or the use of reactances already present a flyback period network of at least 6th order is obtained having at least three resonant frequencies all of which substantially (± 10 percent) satisfy the given expression for $K = 1, 5$ and 7 , respectively. Then substantial freedom of oscillations during the scan period is obtained. In practice, some oscillations are found to occur predominantly as a result of the inevitable losses present in the network.

Both the flyback pulse occurring across the switching means and the flyback pulse applied to the rectifier now include three components, one having a frequency f_α , one having a frequency f_ϵ and one having a frequency f_u . The mutual amplitude ratios between these components determine the shape of the two pulses.

As is known a network having a plurality of resonant frequencies of fixed values may be built up in many different manners; some examples thereof will be given with reference to the Figures. It is found, however, that

independent of the manner in which the network is built up the mutual amplitude ratios of the three components of the flyback pulse occurring across the switching means and hence the shape of this pulse is always dependent in the same manner on the three resonant frequencies f_α , f_ϵ and f_y as well as on the frequencies f_1 and f_2 (lying between f_α and f_ϵ and between f_ϵ and f_y , respectively) at which the input impedance of the network is at a minimum. If the switching means, which generally include one or more diodes or transistors do not permit of the voltage across the switching means reversing its polarity already before termination of the flyback period, the frequencies f_1 and f_2 relative to f_α , f_ϵ and f_y must be such that they satisfy the empirical condition:

$$4.61 (f_1 - f_\alpha / f_\epsilon - f_\alpha) - 1.46 > [1.36 (f_2 - f_\epsilon / f_y - f_\epsilon) - 1]$$

The circuit arrangements according to the invention provide a possibility of obtaining a secondary flyback pulse having a considerably wider and flatter peak than is the case in the above-mentioned known circuit arrangements. As already noted hereinbefore the shape of the secondary flyback pulse is determined by the mutual amplitude ratios between its components. Furthermore it has been found that in whatever manner the network is built up, these mutual amplitude ratios and hence the shape of the secondary flyback pulse are always dependent in the same manner on the location of the possibly present zero transmission frequencies relative to the three resonant frequencies which are present and which are determined by the expression given in the preamble. The zero transmission frequencies of the network are those frequencies at which there is no transfer of energy from the input terminals to the rectifier circuit in the network which is assumed to be free from losses. Unlike the minimum impedance frequencies f_1 and f_2 at the input terminals which are always present and the first of which is always between f_α and f_ϵ and the second is present between f_ϵ and f_y , the number and the location of the zero transmission frequencies is indefinite and is dependent on the structure of the network.

When the network has only one zero transmission frequency f_0 or when a second zero transmission frequency is so high that it does not have substantially any influence, a substantially flat and wide secondary flyback pulse is obtained when this zero transmission frequency lies between f_ϵ and f_y and this in such a manner that the ratio:

$$\frac{f_\alpha (f_0^2 - f_\epsilon^2) (f_y^2 - f_\alpha^2)}{f_\epsilon (f_0^2 - f_\alpha^2) (f_y^2 - f_\epsilon^2)}$$

is between 9 percent and 17 percent.

It is to be noted that it is known to incorporate additional reactances in a flyback EHT and sawtooth current generator, which reactances increase the order of the flyback network. However, these additional reactances envisage objects which deviate entirely from the objects of the present invention. Therefore the proportioning of said extra reactances in the known generators is not such that these three resonant frequencies are obtained.

The invention will be described in detail with reference to the figures shown.

FIGS. 1, 4, 5 and 7 show different embodiments of a flyback EHT and sawtooth current generator according to the invention;

FIGS. 1a, 1b, 1c, 5a, 5b and 7a show different equivalent circuit diagrams of the respective embodiments and

FIGS. 2, 3, 6 and 8 show characteristic fields for further illustration of the proportioning of the different networks.

10 The embodiment of FIG. 1 shows a transformer having a primary winding 2, one or more auxiliary windings 3 rigidly coupled to the primary winding, a secondary winding 4 and a tertiary winding 5. A tap 6 on the primary winding is connected to the positive terminal of 15 a voltage supply source 7 the negative terminal of which is connected to ground. The series arrangement of a plurality of deflection coils 9, a linearity corrector 10 and an S-correction capacitor 11 is arranged between a second tap 8 and the lower end of the primary 20 winding. The tap 8 and the lower end of the primary winding are located symmetrically relative to the tap 6 so that this series arrangement is fed symmetrically relative to ground.

A transistor 12 operating as a switch is provided between the upper end of the primary winding and ground and a capacitor 13 is connected in parallel with this transistor. Said secondary winding 4 is connected to ground at one end and at the other end to a rectifier circuit consisting of a rectifier 14 and a smoothing capacitor 15; the EHT generated by the rectifier is applied to the acceleration anode of a television display tube not further shown.

25 The lower end of the tertiary winding 5 is connected to the tap 6 of the primary winding. A parallel LC-circuit which consists of an inductor 16 and a capacitor 17 is arranged between the upper end of the primary winding and the upper end of the tertiary winding.

30 Switching pulses which periodically cut off the transistor 12 at the end of each scan period are applied between the base and emitter of transistor 12 through a separating transformer 18, a series inductance 19 and a parallel diode 20. The transistor 12 is a so-called slow switching transistor and the elements 19 and 20 are included so as to accelerate the switching off of the transistor at the end of the scan period.

35 To explain the operation of the circuit arrangement described, FIG. 1a shows a first equivalent circuit diagram. In this Figure a switch SW denotes the electronic switch constituted by transistor 12 and diode 20. The portion of the primary winding between the upper end of this winding and the tap 6 of FIG. 1 is denoted by 2'. The inductance of the deflection coils 9 and the linearity corrector 10 is denoted by 21, but transformed to 40 said portion of the primary winding. 11' denotes the S-correction capacitor 11 likewise transformed to said portion. The parasitic capacitance of the secondary winding as well as the input capacitance of the rectifier circuit is denoted by 22. The mutual magnetic couplings between the primary, secondary and tertiary 45 transformer windings are denoted by M1, M2 and M3.

50 A further equivalent circuit diagram is shown in FIG. 1b. In this Figure the S-correction capacitor 11' is omitted because it has such a high value that it exerts substantially no influence during the flyback period. The capacitor 13 is directly provided across the inductor 21 which is admissible because the impedance of the source 7 is very low. Furthermore the circuit diagram

shows the magnetizing inductance 22 of the primary winding, the magnetizing inductance 23 of the tertiary winding and the parasitic capacitance 24 of this winding, the inductor 16 and the capacitor 17, the leakage inductance 25 between the primary and the tertiary winding and in parallel therewith the parasitic capacitance 26 between these windings, the leakage inductance 27 between the tertiary and the secondary winding and in parallel therewith the parasitic capacitance 28 between these windings, the leakage inductance 29 between the primary and the secondary winding and in parallel therewith the parasitic capacitance 30 between these windings and finally the capacitance 22' which represents the transform of the capacitor 22 of FIG. 1a. It is found that the capacitors 24, 28 and 30 have such a low value in practice that they may be left out of consideration and that the inductor 23 has such a high value relative to the inductor 16 that the inductor 23 may be displaced in parallel with the inductor 22. The equivalent circuit diagram of FIG. 1c is obtained when the inductors 21, 22 and 23 are combined to one inductor L1, the inductors 25 and 16 to one inductor L3 and the capacitors 17 and 26 to one capacitor C3 and when furthermore the inductor 29 is denoted by L2, the inductor 27 by L4 and the capacitor 22' by C2 and when finally the capacitor 13 is denoted by C1 in which also the parasitic capacitances of the transistor 12, the primary winding, the deflection coils and the possible auxiliary windings 3 are represented.

During the scan period switch SW is closed. The voltage E from voltage supply source 7 is therefore present across capacitor C1 and also across inductor L1. As a result a (sawtooth) current linearly varying with time will flow through the inductor L1. When, as a result of a pulse applied to the base electrode of transistor 12, switch SW is rendered non-conducting, free oscillations will occur in the network as a result of the magnetic energy present in L1. These oscillations produce pulsatory voltages V1 and V2, the so-called flyback pulses across capacitors C1 and C2, respectively. As soon as the flyback pulse across C1 decreases to the value of the supply voltage -E, that is to say, as soon as the collector potential of transistor 12 becomes negative relative to ground, the collector-base pn-junction of the transistor is in the forward direction and the next scan period commences. Switch SW in the equivalent circuit diagram of FIG. 1c therefore closes automatically as soon as the flyback voltage present across this switch becomes equal to zero.

It is to be noted that the sawtooth current in the circuit diagram of FIG. 1 flows during the first part of the scan period through the diode 20, the base-collector junction of the transistor and subsequently through the transformer and the deflection coils to the voltage supply source and thus feeds back energy to the voltage supply source. Some time after the commencement of the scan period the base-emitter junction of the transistor is rendered conducting by means of the pulses applied to the base electrode of the transistor so that during the second part of the flyback period the sawtooth current now reversed in polarity can flow from the voltage supply source through the transformer and the deflection coils and subsequently through the collector electrode and the emitter electrode of the transistor to ground, while the voltage supply source supplies energy to the network.

It is to be ensured that during the scan period only a sawtooth current flows through L1 and that free oscillations do not occur as a result of electrical or magnetic energy present in the inductors L2, L3 and L4 and capacitors C2 and C3. Such a scan period without oscillations is obtained if it is ensured that the currents flowing through L2, L3 and L4 are all equal to zero during the entire scan period and therefore also at the commencement and the end of the flyback period and that the voltages across C3 and C2 are equal to zero and are equal to the battery voltage -E, respectively. To satisfy this condition the following two relations are to apply for each resonant frequency α of the flyback period network, thus of the network in case of an open switch SW:

$$\alpha\tau = K\pi + 2\phi_\alpha \quad (I)$$

$$\alpha t g \phi_\alpha = (i_o' / i_o) \quad (II)$$

In this relation τ is the duration of the flyback period, K is each odd positive integer, i_o is the value of the sawtooth current at the commencement of the flyback period, i_o' is the derivative with time of this current at the commencement of the flyback period and ϕ_α is a phase angle. It is possible to eliminate ϕ_α from the two equations. Then a power series in $\tau i_o' / i_o$ is produced for $\alpha\tau$. If this series is limited to the first two terms it is found that:

$$\alpha\tau = K\pi + (2/K\pi) (\tau i_o' / i_o)$$

When a purely linear sawtooth current flows through L1 and hence through the deflection coils, there applies as an approximation: $(\tau i_o' / i_o) = (2\tau/T - \tau)$ in which $T - \tau$ is the duration of the scan period. When, however, the deflection current has a slightly S-shaped character as a result of the S-correction capacitor of FIG. 1, which character is conventional in television display apparatus, there applies as an approximation: $(\tau i_o' / i_o) = (2\tau/T - \tau) (1 - \frac{2}{3}S)$ in which S is the relative reduction of the slope of the deflection current at the end of the scan period relative to this slope in the centre of the scan period. The above-mentioned condition for $\alpha\tau$ then changes to:

$$\alpha\tau = K\pi [1 + (4/K^2\pi^2) (\tau/T - \tau) (1 - \frac{2}{3}S)]$$

with $f_\alpha = (\alpha/2\pi)$ there follows that

$$f_\alpha = (K/2\tau) [1 + (4/K^2\pi^2) (\tau/T - \tau) (1 - \frac{2}{3}S)] \quad (III)$$

As already noted hereinbefore the equations I and II and hence also equation III must apply to each resonant frequency of the flyback network in order to obtain a scan without oscillations. In the circuit arrangements according to the invention the flyback network is built up in such a manner that a network of the 6th order at a minimum is obtained having at least three resonant frequencies f_α , f_ϵ and f_ν and the proportioning of the network values is chosen in such a manner that f_α satisfies equation III for $K = 1$, f_ϵ for $K = 5$ and f_ν for $K = 7$.

As is known (see for example the book "Theorie der Wisselströmen" by Prof. Ir. B.D.H. Tellegen, Vol. III particularly section 2, 351) the order of a network is

determined by the number of capacitor voltages which can be given independently of each other and by the number of induction currents which can be given independently of each other. In the network of FIG. 1c all capacitor voltages and all induction currents can be given independently of each other and the network therefore has the order 7. However, there is one direct current solution namely in the mesh formed by L2, L3 and L4. Since furthermore the network is supposed to be without resistors, the equation for the free oscillations of the network is: $p(p^2 + \alpha^2)(p^2 + \epsilon^2)(p^2 + y^2) = 0$ in which p is the differential operator transformed in accordance with the Laplace arithmetic and α, ϵ and y represent the three resonant frequencies of the flyback network, expressed in rad/sec.

A further consideration of the equivalent circuit diagram of FIG. 1b shows that seven inductors are present therein whose currents can all be given independently of each other; however, only three voltages of the seven capacitors present can be given independently of each other, for example the voltages of the capacitors 13, 24 and 22', then the voltages across capacitors 17, 26, 28 and 30 are determined. The network therefore has the order 10. However, there are four direct current meshes present, namely a first mesh 21, 22, a second mesh 22, 16, 23, a third mesh 16, 25 and a fourth mesh 25, 27, 29. The equation for the free oscillations therefore becomes:

$$p^4(p^2 + \alpha^2)(p^2 + \epsilon^2)(p^2 + y^2) = 0$$

The simplifications which are made at the change-over from the circuit diagram of FIG. 1b to that of FIG. 1c thus have not resulted in a reduction of the number of resonant frequencies.

The above given relations apply to a network in which energy is not dissipated. This is of course not the case in practice because the network elements are not completely without resistance and because energy is drawn from the network through the rectifier circuit 14-15 and through the auxiliary windings 3. Therefore it will not be possible in practice to realize a scan which is completely without any oscillation. However, since the electromagnetic energy circulating in the flyback network is in practice considerably larger than the dissipated energy, the given relations remain approximately applicable and for a scan which is sufficiently without oscillations the three resonant frequencies f_α, f_ϵ and f_y may therefore not deviate by more than 10% from the value found in equation III.

When the input impedance of the network is determined as a function of the frequency, i.e. the impedance at the terminals to which the switching means SW are connected, this input impedance will be at a maximum at the three resonant frequencies α, ϵ and y . As is known a frequency is present between α and ϵ and between ϵ and y at which the input impedance is at a minimum (in a network without resistors equal to 0). These two zero impedance frequencies are hereinafter denoted by f_1 and f_2 and the associated angular frequencies are denoted by β_1 and β_2 . Thus there always applies that:

$$\alpha < \beta_1 < \epsilon < \beta_2 < y.$$

The flyback pulse which will be produced during the flyback period at the input of the network has three sine functions, one for each frequency, as a result of the three resonant frequencies of the network. When

for each of the three resonant frequencies equations III is satisfied it is possible to write for the flyback voltage V_1 across capacitor C_1 :

$$V_1 = A_\alpha \frac{\sin(\alpha t - \phi_\alpha)}{\sin \phi_\alpha} + A_\epsilon \frac{\sin(\epsilon t - \phi_\epsilon)}{\sin \phi_\epsilon} + A_y \frac{\sin(yt - \phi_y)}{\sin \phi_y} \quad (IV)$$

in which t represents the time during the flyback period hence $0 \leq t \leq \tau$ and in which $\phi_\alpha, \phi_\epsilon$ and ϕ_y are the phase angles which follow from equation I which applies to each resonant frequency:

$$\begin{aligned} \phi_\alpha &= (\alpha\tau/2) - (\pi/2) \\ \phi_\epsilon &= (\epsilon\tau/2) - (8\pi/2) \\ \phi_y &= (y\tau/2) - (y\pi/2) \end{aligned} \quad (V)$$

For A_α, A_ϵ and A_y we find that:

$$\begin{aligned} A_\alpha &= E \frac{(1/\alpha^2 - 1/\beta_1^2)(1/\alpha^2 - 1/\beta_2^2)}{(1/\alpha^2 - 1/\epsilon^2)(1/\alpha^2 - 1/y^2)} \\ A_\epsilon &= E \frac{(1/\epsilon^2 - 1/\beta_1^2)(1/\epsilon^2 - 1/\beta_2^2)}{(1/\epsilon^2 - 1/\alpha^2)(1/\epsilon^2 - 1/y^2)} \\ A_y &= E \frac{(1/y^2 - 1/\beta_1^2)(1/y^2 - 1/\beta_2^2)}{(1/y^2 - 1/\alpha^2)(1/y^2 - 1/\epsilon^2)} \end{aligned} \quad (VI)$$

These values are thus found to be dependent only on the supply voltage E and on the mutual location of the β_1 and β_2 frequencies relative to α, ϵ and y .

The shape of the flyback pulse is dependent on the mutual amplitude ratios of the three respective sine oscillations. The amplitudes are, respectively, $(A_\alpha/\sin \phi_\alpha), (A_\epsilon/\sin \phi_\epsilon)$ and $(A_y/\sin \phi_y)$. Since in practical cases $\phi_\alpha, \phi_\epsilon$ and ϕ_y are only small phase angles, $\sin \phi_\alpha, \sin \phi_\epsilon$ and $\sin \phi_y$ may be replaced by $\tan \phi_\alpha, \tan \phi_\epsilon$ and $\tan \phi_y$ with which the amplitudes change to

$$\begin{aligned} (A_\alpha / \tan \phi_\alpha), (A_\epsilon / \tan \phi_\epsilon) \text{ and } (A_y / \tan \phi_y) \\ (\alpha A_\alpha / \alpha \tan \phi_\alpha), (\epsilon A_\epsilon / \epsilon \tan \phi_\epsilon) \text{ and } (y A_y / y \tan \phi_y) \end{aligned}$$

In view of the fact that equation II applies to each resonant frequency, $\alpha \tan \phi_\alpha = \epsilon \tan \phi_\epsilon = y \tan \phi_y = i'_o/i_o$. For the ratio P_1 between the amplitudes of the ϵ and the α oscillations it is then found that $P_1 = (\epsilon A_\epsilon / \alpha A_\alpha)$ and that for the ratio P_2 between the amplitudes of the Y and the α oscillations it is found that $P_2 = (y A_y / \alpha A_\alpha)$. When the above given expressions for A_α, A_ϵ and A_y are substituted therein, there follows:

$$\begin{aligned} P_1 &= -\frac{\alpha(\beta_1^2 - \epsilon^2)(\beta_2^2 - \epsilon^2)(y^2 - \alpha^2)}{\epsilon(\beta_1^2 - \alpha^2)(\beta_2^2 - \alpha^2)(y^2 - \epsilon^2)} \\ P_2 &= -\frac{\alpha(\beta_1^2 - y^2)(\beta_2^2 - y^2)(\epsilon^2 - \alpha^2)}{y(\beta_1^2 - \alpha^2)(\beta_2^2 - \alpha^2)(\epsilon^2 - y^2)} \end{aligned} \quad (VII)$$

FIG. 2 shows a characteristics field in which horizontally β_1 varies from α to ϵ and vertically β_2 varies from ϵ to y . The Figure shows lines of constant P_1 and constant P_2 . These lines clearly show that as the left top corner of the field is more and more approached the ratio

P_1 increases; that is to say, the amplitude of the ϵ component relative to the amplitude of the α component increases. Likewise the amplitude of the y -component will increase relative to that of the α -component as the left bottom corner of the field is approached. The field furthermore shows a shaded area. In this area the amplitude of the ϵ -component and/or the amplitude of the y -component is so large relative to the amplitude of the α -component that the flyback pulse (the voltage V_1) occurring across capacitor C_1 becomes lower than the supply voltage $-E$ already before the flyback period τ given in equation I has elapsed. This results in the transistor 12 conducting prematurely. The scan period then commences while electrical and/or magnetical energy is still present in the network elements which gives rise to free oscillation phenomena in the scan period. For a scan without oscillations it is therefore necessary that:

1. the three resonant frequencies α , ϵ and y of the network satisfy equation III,

2. either switching means are used which remain non-conducting during the entire flyback period even when the voltage across the switching means reverses its sign, or the β_1 and β_2 frequencies are located in the area which is not shaded in FIG. 2. The latter condition may approximately be expressed by the empirical relation:

$$4,61 (\beta_1 - \alpha/\epsilon - \alpha) - 1,46 > [1,36 (\beta_2 \epsilon/y - \epsilon) - 1]^2$$

The characteristics field and the shaded area of FIG. 2 are determined by means of a computer. In this case α , ϵ and y are determined in accordance with equation III with $K = 1, 5$ and 7 , respectively, and at a flyback ratio $\tau/T = 0.18$ and an S-correction factor $S = 0$. Modification of this flyback ratio and of the S-correction factor within limits occurring in practice results, however, hardly in a change of the picture shown in FIG. 2.

It is furthermore to be noted that the above given equations and conditions are not limited to the network of FIG. 1c, but generally apply to any network having three resonant frequencies, thus irrespective of the manner in which the network is actually composed of the different network elements. Of course the manner in which the α , ϵ , y , β_1 and β_2 frequencies are dependent on the separate network elements is different for each network. It is therefore hardly useful to determine these dependences, also because the values of the different network elements are difficult to determine in practice due to their frequently entire or partly parasitic character. The five mentioned frequencies α , ϵ , y , β_1 and β_2 are, however, simply measurable to which end the following method may be carried out. The arrangement in which the generator is included is switched off so that the voltage supply source 7 does not provide voltage and the base connection of transistor 12 is disconnected. A tone generator which covers the relevant frequency range is connected to the collector electrode of the transistor through a sufficiently high impedance. Furthermore a voltage measuring instrument having a sufficiently high input impedance is connected to the collector electrode, for example, an oscilloscope or a valve voltmeter. By varying the frequency of the tone generator the frequencies are found at which the measured voltage is at a maximum, i.e. the resonant frequencies α , ϵ and y , as well as the frequencies therebetween at which the measured voltage is at a minimum, i.e. the minimum impedance frequencies β_1 and β_2 .

As described in the preamble it is important for a low EHT R_t that the flyback pulse V_2 applied to the rectifier circuit during the flyback period has a peak which is as wide and as flat as possible. Likewise as the flyback pulse V_1 the flyback pulse V_2 consists of three components, one of the frequency α , one of the frequency ϵ and one of the frequency y . When α , ϵ and y all satisfy equation III, we find for V_2 :

$$V_2 = B_\alpha \frac{\sin(\alpha t - \theta_\alpha)}{\sin \theta_\alpha} + B_\epsilon \frac{\sin(\epsilon t - \theta_\epsilon)}{\sin \theta_\epsilon} + B_y \frac{\sin(y t - \theta_y)}{\sin \theta_y} \quad (VIII)$$

in which for B_α , B_ϵ and B_y there applies:

$$B_\alpha = E' \frac{(1/\alpha^2 - 1/\alpha_0^2) (1/\alpha^2 - 1/\delta_1^2)}{(1/\alpha^2 - 1/\epsilon^2) (1/\alpha^2 - 1/y^2)} \quad (IX)$$

$$B_\epsilon = E' \frac{(1/\epsilon^2 - 1/\delta_0) (1/\epsilon^2 - 1/\delta_1^2)}{(1/\epsilon^2 - 1/\alpha^2) (1/\epsilon^2 - 1/y^2)} \quad (IX)$$

In these formulas E' is a constant which is proportional to the supply voltage E and which is equal to E in the circuit diagram of FIG. 1c. δ_0 and δ_1 are the zero transmission frequencies of the network, i.e. those frequencies at which there is no energy transmission in a network which is completely without resistors between the input terminals of the network and the output terminals to which the rectifier circuit is connected. Due to the inevitable losses some energy transmission will take place at these frequencies in practice.

The above given expressions for B_α , B_ϵ and B_y generally apply to each network having three resonant frequencies which has a scan period without oscillations in the manner described. However, unlike the frequencies β_1 and β_2 both of which are always present and the lowest (β_1) of which is always between α and ϵ and the highest (β_2) is always between ϵ and y both zero transmission frequencies may not always be present. In many circuit arrangements according to the invention only one zero transmission frequency (δ_0) will be present or the second zero transmission frequency (δ_1) is so high that it may be left out of consideration. Thus in the equivalent circuit diagram of FIG. 1c only one zero transmission frequency is present namely the frequency at which the two-pole formed by L_2 , L_3 , C_3 and L_4 is in parallel resonance, hence $\delta_0^2 = (L_2 + L_3 + L_4)/C_3L_3 (L_2 + L_4)$.

The equations for B_α , B_ϵ and B_y then change to:

$$B_\alpha = E' \frac{1/\alpha^2 (1/\alpha^2 - 1/\delta_0^2)}{(1/\alpha^2 - 1/\epsilon^2) (1/\alpha^2 - 1/y^2)} \quad (X)$$

$$B_\epsilon = E' \frac{1/\epsilon^2 (1/\epsilon^2 - 1/\delta_0^2)}{(1/\epsilon^2 - 1/\alpha^2) (1/\epsilon^2 - 1/y^2)} \quad (X)$$

$$B_y = E' \frac{1/y^2 (1/y^2 - 1/\delta_0^2)}{(1/y^2 - 1/\alpha^2) (1/y^2 - 1/\epsilon^2)} \quad (X)$$

The shape of the flyback pulse V_2 is determined by the mutual amplitude ratios of the three components. When S_1 represents the ratio between the amplitude of the ϵ -component and the amplitude of the α -compo-

ment and when S_2 represents the ratio between the amplitude of the y -component and the amplitude of the α -component, there applies in a corresponding manner as for the ratios P_1 and P_2 of the flyback pulse V_1 that:

$$S_1 = (-\epsilon B_\epsilon / \alpha B_\alpha) \text{ and } S_2 = (B_y / \alpha B_\alpha)$$

With the given expressions for B_α , B_ϵ and B_y it is found for the case where there is only one zero transmission frequency:

$$S_1 = -\frac{\alpha(\delta_0^2 - \epsilon^2)(y^2 - \alpha^2)}{\epsilon(\delta_0^2 - \alpha^2)(y^2 - \epsilon^2)} \quad (XI)$$

$$S_2 = -\frac{\alpha(\delta_0^2 - y^2)(\epsilon^2 - \alpha^2)}{y(\delta_0^2 - \alpha^2)(\epsilon^2 - y^2)}$$

When the ratio S_1 is determined in accordance with values of α , ϵ and y laid down in accordance with equation III and by a given choice of δ_0 the ratio S_2 is of course also determined. The relationship between S_1 and S_2 is as follows:

$$\alpha + \epsilon S_1 + y S_2 = 0 \quad (XII)$$

It will be evident from the foregoing that when the network has only one zero transmission frequency, the location of this zero transmission frequency relative to α , ϵ and y is decisive for the shape of the flyback pulse V_2 . It follows from a further consideration of the three components which jointly constitute the flyback pulse V_2 that when α , ϵ and y satisfy equation III with $K = 1$, 5 and 7 respectively, it is necessary for a pulse having a wide and flat peak that both S_1 and S_2 are negative. This is possible only when δ_0 lies between ϵ and y while a possible second zero transmission frequency δ_1 must be higher than y .

For an acceptable shape of the flyback pulse the zero transmission frequency δ_0 will lie between ϵ and y in such a manner that S_1 is between -0.09 and -0.17 while an optimum flyback pulse is obtained at an S_1 of approximately -0.14 .

Unlike the frequencies β_1 and β_2 , which as stated above can be determined in a simple manner in a practical generator this is considerably more difficult for the zero transmission frequencies. This is mainly a result from the fact that in practical circuit arrangements the impedance level at the output terminals coupled to the rectifier is very high. The parasitic capacitances of measuring equipment connected to the terminals then cause a considerable unwanted variation of the proportioning of the network.

When, however, the structure of the network, in this case the structure of the equivalent circuit diagram is known, it is possible in many cases to determine the relationship between the zero transmission frequencies and the zero impedance frequencies β_1 and β_2 and thus to determine the location of the zero transmission frequencies through measurement of β_1 and β_2 . Thus for the equivalent circuit diagram of FIG. 1c there applies the following relation

$$\delta_0^2 = \frac{\alpha^2 \epsilon^2 + \alpha^2 y^2 + \epsilon^2 y^2 - \beta_1^2 \beta_2^2 - \alpha^2 \epsilon^2 y^2 \{1/\beta_1^2 + 1/\beta_2^2\}}{\alpha^2 + \epsilon^2 + y^2 - \beta_1^2 - \beta_2^2 - \frac{\alpha^2 \epsilon^2 y^2}{\beta_1^2 \beta_2^2}} \quad (XIII)$$

FIG. 3 shows with the aid of the above-mentioned equation the field of FIG. 2, but in this case with lines of constant δ_0 . Since the frequency δ_0 also determines

the ratios S_1 and S_2 and hence the shape of the flyback pulse V_2 these are also lines where the flyback pulse V_2 has a constant shape. The reference a denotes the line at which the ratio $S_1 = -0.17$ while $S_2 = -0.14$ is given on line b and $S_1 = -0.09$ on line c . This field also shows the shaded area already mentioned with reference to FIG. 2. In case of an EHT and sawtooth current generator for which at least the equivalent circuit diagram of FIG. 1c substantially applies the frequencies β_1 and β_2 will therefore be chosen between the lines a and c of FIG. 3 and preferably in the non-shaded area.

In the embodiment of FIG. 4 corresponding elements have the same reference numerals as those in FIG. 1. Unlike FIG. 1 the primary winding consists of two identical halves $2a$ and $2b$ while the voltage supply source 7 is arranged between the two halves. The series arrangement of S-capacitor 11, linearity corrector 10 and deflection coils 9 is symmetrical relative to ground between the high end of the upper half $2a$ and the low end of the lower half $2b$. The transistor 12 and the capacitor 13 are included between taps 32 and 33 of the two primary halves which are arranged symmetrically relative to ground. The tertiary winding 5 is also connected between these taps and this through the LC-circuit 16 and 17 and through a direct voltage isolation capacitor 31 of large value. The advantage of the network of FIG. 4 relative to that of FIG. 1 is that not only the series arrangement of the elements 9, 10 and 11 but also the primary winding, the transistor 12, the capacitor 13 and substantially the tertiary winding 5 are located symmetrically relative to ground; this yields a considerable reduction of the parasitic radiation of the generator. The equivalent circuit diagram of the flyback network of this embodiment is the same as shown in FIG. 1c so that also the above described phenomena are the same.

It is to be noted that in the embodiments of FIG. 1 and FIG. 4 the leakage inductance between the primary and secondary windings do not play a principal role. In fact, if in the equivalent diagram of FIG. 1c the inductor L_2 representing this leakage is omitted, a network still remains having three resonant frequencies for which all considerations described above apply. The leakage between the secondary and the tertiary winding represented in FIG. 1c by the inductor L_4 plays, however, a very essential role. In fact, when the coupling between secondary and tertiary winding is tight in such a manner that L_4 in the equivalent circuit diagram can be replaced by a short circuit, the voltages across capacitors C_1 , C_2 and C_3 can no longer be given independently of each other and therefore a 5th order network remains having one direct current solution (through L_2 and L_3). The network then only has two resonant frequencies.

The embodiment of FIG. 5 deviates from the embodiment of FIG. 1 in that the parallel arrangement of the inductor 16 and the capacitor 17 is located between the high end of the primary winding 2 at one end and the capacitor 13 and the collector of the transistor 12 at the other end. An important advantage of this circuit relative to the circuit arrangement of FIGS. 1 and 4 is that the tertiary transformer winding 5 can be omitted. For the arrangement of FIG. 5 a simplified equivalent circuit diagram can be set up as is shown in FIG. 5a. In this FIG. C_1 represents the capacitor 13 and the output capacitance of the transistor, L_3 and C_3 represent the inductor 16 and the capacitor 17, respectively, L_1 represents the transformed inductance of the deflection

coils 9 and the linearity corrector 10 as well as the magnetizing inductance of the transformer, L2 represents the leakage inductance between the primary winding and the secondary winding and C2 represents the parasitic capacitance of the secondary winding and the input capacitance of the rectifier circuit all transformed to the primary side. The network of FIG. 5a is a 6th order network having three resonant frequencies α , ϵ and y . For a scan period without oscillations there must not apply both at the beginning and at the end of the flyback that the current through L3 and the voltage across C3 are zero because the sawtooth current flowing through L1 also flows through L3. The conditions for a scan period without oscillations therefore are that at the commencement and end of the flyback:

1. the current through L2 = 0
2. the voltage across L2 = 0, hence the voltage across C2 is equal to the voltage across L1
3. the current through L3 is equal to the current through L1, hence the current through C3 is equal to 0
4. the ratio of the voltage across C3 and L3 and the voltage across L1 is the same as the ratio between the inductor L3 and the inductor L1.

It is found that these four requirements are satisfied when the above given equations I and II are satisfied, while i_0 and i'_0 again represent the current through L1 and the derivative of this current, respectively at the end of the scan period. The equations I and II and hence the equation III derived therefrom are found to be generally applicable as conditions for a scan without oscillations. Also equations IV, VI and VII which relate to the shape of the flyback pulse occurring across switch SW are found to be generally applicable for a flyback network having three resonant frequencies. Finally also the equations VIII and IX for any such network are found to be applicable. Since the equivalent circuit diagram of FIG. 5a has only one zero transmission frequency, namely the frequency at which L3 and C3 are in resonance, the equations X, XI and XII also apply to this equivalent circuit diagram.

The relationship between the zero transmission frequencies and the frequencies α , ϵ_y , β_1 and β_2 which was given for the circuit diagram of FIG. 1c by equation XIII is, however, different. This relationship is obtained for the equivalent circuit diagram of FIG. 5a by choosing for δ_0^2 the highest root from the following square equation in δ_0^2

$$\delta_0^4 (\alpha^2 + \epsilon^2 + y^2 - \beta_1^2 - \beta_2^2) - \delta_0^2 (\alpha^2 \beta^2 + \alpha^2 y^2 + \epsilon^2 y^2 - \beta_1^2 \beta_2^2) + \alpha^2 \beta^2 y^2 = 0.$$

When the lines of constant δ_0 and hence the lines of constant S_1 and S_2 are determined with the aid of this equation in the $\beta_1 - \beta_2$ field, the field of FIG. 6 is found. As can be seen the lines for $S_1 = -0.09$, -0.14 and -0.17 vary in the non-shaded area of this field in approximately the same manner as in the field of FIG. 3. For an optimum secondary flyback pulse the β_1 and β_2 frequencies will therefore be located in an approximately corresponding manner.

It is to be noted that since V_2 represents the voltage across the secondary winding 4, the equivalent circuit diagram of FIG. 5a would be correct when the low end of the secondary winding were directly connected to ground. However, since this low end is connected to the high end of capacitor 13 the voltage $V_2' = V_1 + NV_2$ is actually applied to the rectifier in which N is the

transformation ratio of the transformer. The equivalent circuit diagram of FIG. 5 then becomes actually the diagram shown in FIG. 5b in which T is an ideal transformer having a transformation factor N because the magnetizing inductance and the leakage inductance of the transformer are already accounted for in L1 and L2. It will be evident that when N is large relative to 1, the flyback pulse V_1 substantially does not exert any influence on the output pulse V_2' and the output pulse 10 will therefore have substantially the same shape as the pulse V_2 . When N is not large relative to 1 such as may occur, for example, in valve circuits the share of V_1 in V_2' will have to be taken into account. It is found that even now the equations VIII and IX maintain their general applicability if in the left member of VIII V_2' instead of V_2 is read and if δ_0 and δ_1 are defined as those zero transmission frequencies at which no energy transmission occurs to the actual output terminals, hence those frequencies at which $NV_2 + V_1 = 0$. The circuit diagram of FIG. 5b has two such zero transmission frequencies. When N is large relative to 1, the first zero transmission frequency (δ_0) is located very closely to the resonant frequency of L3 and C3 while the second (δ_1) is considerably much higher.

25 Corresponding considerations apply when, for example, in the embodiments of FIG. 1 and FIG. 4 the low end of the secondary winding 4 is connected to the high end of the tertiary winding 5 instead of to ground. The two windings 4 and 5 then together constitute substantially one winding having a tap leading to the LC-circuit 16-17.

30

35 A drawback of the embodiment of FIG. 5 is the following. As a result of the losses present in the flyback network and tolerance deviations a scan which is completely without any oscillation cannot be realized in practice. In the embodiments of FIG. 1 and FIG. 4 the series arrangement of deflection coils, linearity corrector and S-capacitor is arranged through the primary winding substantially directly across switching transistor 12. This is still more evident from the equivalent circuit diagram of FIG. 1c where the inductor L1 is directly connected to switch SW. Scan oscillations which occur in the section L2, C2, L3, C3 and L4 cannot reach the deflection coils (L1) because L1 is short-circuited through the now conducting switch SW and through the voltage supply source. In the embodiment of FIG. 5 this is, however, not the case; scan oscillations which occur across the resonant circuit L3, C3 are also present across L1 and hence across the deflection coils. 45

50

55 This causes unwanted modulation of the deflection in the display tube of the television apparatus.

While obviating a tertiary transformer winding this drawback is not present in the embodiment of FIG. 7. This embodiment has the same symmetrical structure as that of FIG. 4. The parallel arrangement of inductor 16 and capacitor 17 is, however, arranged in series with capacitor 13 while the tertiary winding 5 is omitted. FIG. 7a shows the equivalent circuit diagram having the most important network elements. As can be seen the flyback network is of the 6th order because six inductors and capacitors are present and because all capacitor voltages and induction currents can be given independently of each other. In addition, there are no direct current or direct voltage solutions present so that the 6th order network has again three resonant frequencies α , ϵ and y for which all given relations I to IX inclusive apply. The network has one zero transmission frequency δ_0 namely the frequency at which the two-

15

pole constituted by C1, C3 and L3 is in series resonance.

$$\delta_0^2 = 1/L_3 (C_1 + C_3),$$

so that also the equations X, XI and XII apply.

The relationship between δ_0 and the frequencies β_1 and β_2 is very simple in this case because the series resonant frequency of the dipole C1, C3, L3 is also one of the two zero impedance frequencies at the input terminals, hence $\delta_1 = \beta_1$ or $\delta_0 = \beta_2$. Since, as stated above, a flyback pulse V_2 having a wide and flat peak necessitates that δ_0 lies between ϵ and γ and since furthermore β_1 is never between ϵ and γ and β_2 is always between ϵ and γ it follows that for δ_0 there applies that $\delta_0 = \beta_2$.

The lines of constant δ_0 and hence of constant S_1 and S_2 in the $\beta_1 - \beta_2$ field are therefore horizontal straight lines. In FIG. 8 this field is shown with the position of the lines in which $S_1 = -0.09, -0.14$ and -0.17 respectively.

It is known from the network theory that the two-pole constituted by C1, C3 and L3 may be replaced by an equivalent network comprising the series arrangement of L4 and C1 and the capacitor C3 in parallel with this series arrangement. The values of the components are then to be modified accordingly.

Instead of being arranged in series with the capacitor 13, as shown in FIG. 7, the circuit 16-17 may be arranged, for example, in series with the deflection coils in which the $\beta_1 - \beta_2$ field of FIG. 8 continues to apply. Such a circuit arrangement has, however, the drawback that possible remaining scan oscillations occur across the deflection coils.

As described hereinbefore it is impossible in practice to give complete and exact proportioning measures for the respective circuit elements which lead to the above-given frequency values. In practice the correct proportioning will be found by variation of the different circuit elements; namely by the choice of the number of turns of the transformer windings; the manner of winding these windings so that the parasitic capacitance as well as the mutual leakage thereof can be influenced within given limits, the choice of the various taps as well as the inductance and capacitances of the reactances connected to the transformer. The following considerations may be useful for this purpose.

1. If in all embodiments shown the parallel LC-circuit 16-17 is short-circuited, a network is always obtained having only two relevant resonant frequencies and of which the first is substantially equal to α and the second lies between ϵ and γ . The network having a short-circuited LC-circuit will thus firstly be proportioned in such a manner that the first of the two occurring resonant frequencies is approximately equal to α and the second lies between ϵ and γ ; subsequently the LC-circuit is provided which is controlled in such a manner that a scan without oscillations as well as a flyback pulse V_2 having a wide and flat peak is produced.

2. The frequency α will generally be equal to $1/\sqrt{L_1(C_1 + C_2)}$. This frequency is thus determined in a first approximation by the inductance of the deflection coils and the linearity corrector, by the location of the tap on the primary winding to which these elements are connected as well as by the sum of the primary tuning capacitor 13 and the parasitic capacitance of the secondary winding and of the rectifier circuit which capacitance is multiplied by the square value of the transformation ratio of the transformer.

16

3. The second resonant frequency mentioned under item 1 and occurring when the LC-circuit is short-circuited is determined to a considerable extent by the series arrangement of C1 and C2 and by the leakage inductance (L2 parallel to L4 in FIG. 1c and L2 in FIG. 5a 5b and 7a). Since this second resonant frequency must be between the ultimately desired values of ϵ and γ and since these are comparatively high frequencies, this means that the leakage inductance between the primary and secondary winding (in FIGS. 1 and 4 mainly the leakage inductance between tertiary and secondary windings) and the capacitance of the secondary winding are to be comparatively low. In the embodiments of FIGS. 1 and 4 the secondary and tertiary windings therefore be preferably wound across each other on the transformer core while in the embodiments of FIGS. 5 and 7 this is the case with the primary and the secondary windings. The parasitic capacitance of the secondary winding may be maintained low by winding this 10 winding in a narrow and high manner; however, this measure increases the leakage inductance with the other windings so that a comprise is to be found. When a voltage multiplying rectifier circuit is used, the number of turns of the secondary winding and hence both 15 the leakage inductance and the parasitic capacitance of this winding is lower. Proportioning then becomes considerably simpler. A drawback of such a voltage multiplier is, however, that the EHT R_t is increased thereby.

Finally the following is to be noted. In the generators 30 according to the invention the three resonant frequencies α , ϵ and γ of the flyback network at least substantially satisfy equation III for K being equal to 1, 5 and 7, respectively. In practical cases the lowest resonant frequency α will always satisfy equation III for K = 1. 35 However, it remains possible for the three resonant frequencies to satisfy equation III for K being equal to, for example, 1, 3 and 5, respectively, or 1, 3 and 7, respectively. A scan without oscillations can then also be realized. It is, however, found that for a wide and flat secondary flyback pulse in the cases 1, 3, 5 and 1, 3, 7 the lowest zero transmission frequency must be considerably much lower than in the case 1, 5, 7, namely lower than the second resonant frequency. In practice, this 40 leads to circuit arrangements which cannot be realized. 45 A 1, 3, 5 generator is, for example, possible with a scan which is sufficiently without oscillations but in which the zero transmission frequency (frequencies) is(are) anything but optimum. The secondary flyback pulse consequently has a much less wide peak as in the circuit arrangements according to the invention. The EHT R_t will hardly be lower in such a circuit arrangement than in the known circuit arrangements which have 50 only two resonant frequencies.

Theoretically it is possible to make a network of at 55 least 8th order having four or more resonant frequencies with the aid of an additional number of reactances which are either or not parasitic, while the fourth resonant frequency satisfies equation III for K being, for example, equal to 9 or 11. It is found, however, that such a high resonant frequency hardly exerts any influence on the shape of the flyback pulses and in addition cannot be handled in practice because the inductances and/or capacitances which lead to these extra resonant frequencies are very low.

60 What is claimed is:

1. A flyback EHT and sawtooth current generator particularly for television display apparatus including

switching means which are periodically non-conducting during a flyback period τ and are conducting during a scan period $T - \tau$ and a network having input terminals connected to the switching means, the network comprising a transformer having at least one primary winding and possibly one or more coils connected thereto through which said sawtooth current flows during the scan period, and a secondary winding to which a rectifier circuit is connected for generating said EHT from the voltage pulses occurring during the flyback period at the secondary winding, said network, during the flyback period, having a first resonant frequency f_α which is at least substantially equal to the expression

$$K/2 \tau \{1 + (4/K^2\pi^2) (\tau/T - \tau) (1 - \frac{2}{3} S)\}$$

wherein $K = 1$ and S is a correction factor which is equal to the relative reduction of the slope of the sawtooth current at the end of the scan period relative to this slope in the middle of the scan period, and a second resonant frequency f_ϵ which is at least substantially equal to the said expression for $K = 5$, characterized in that in said network further reactances are present which increase the order of the network during the flyback period to a minimum of 6 in such a manner that the network has a third resonant frequency f_y which is at least substantially equal to the above-mentioned expression for $K = 7$.

2. A flyback EHT and sawtooth current generator as claimed in claim 1, characterized in that for the two frequencies f_1 and f_2 located between f_α and f_ϵ and between f_ϵ and f_y , respectively, at which the impedance at the input terminals of the network is at a minimum there applies that

$$4.61 (f_1 - f_\alpha) / f_\epsilon - f_\alpha) - 1.46 > [1.36 (f_2 - f_\epsilon) / f_y - f_\epsilon) - 1]^2.$$

3. A flyback EHT and sawtooth current generator as claimed in claim 1, characterized in that said network has at least one zero transmission frequency in which the energy transfer from the input terminals to the rectifier circuit is at least substantially zero, said zero

transmission frequency f_0 being located between f_ϵ and f_y in such a manner that the ratio:

$$\frac{f_\alpha (f_0^2 - f_\epsilon^2) (f_y^2 - f_\alpha^2)}{f_\epsilon (f_0^2 - f_\alpha^2) (f_y^2 - f_\epsilon^2)}$$

is larger than 9 percent and is smaller than 17 percent.

4. A flyback EHT and sawtooth current generator as claimed in claim 1, in which the transformer has a tertiary winding and in which the switching means and a tuning capacitor are connected to the primary winding, characterized in that the tertiary winding is connected through a parallel LC-circuit to the primary winding and that the network, at least due to the inductance of said coils, the capacitance of the tuning capacitor, the parasitic capacitance of the secondary winding and the rectifier circuit, the inductance and the capacitance of said parallel LC-circuit and the leakage inductance between the secondary and tertiary winding constitutes a network of a minimum 6th order with the said three resonant frequencies.

5. A flyback EHT and sawtooth current generator as claimed in claim 1 in which a tuning capacitor is connected through a connection to the primary winding of the transformer, characterized in that a parallel LC-circuit is included in said connection and that the network, at least due to the inductance of said coils, the capacitance of the tuning capacitor, the parasitic capacitance of the secondary winding and the rectifier circuit, the inductance and the capacitance of said parallel LC-circuit and the leakage inductance between the primary and the secondary winding constitutes a network of a minimum of 6th order with the said three resonant frequencies.

6. A flyback EHT and sawtooth current generator as claimed in claim 5, characterized in that the switching means are arranged across the series arrangement of the said tuning capacitor and the parallel LC-circuit.
